FIG. 1

FIG. 2

FIG. 3

FIG. 4

FIGURE 1 is a perspective view illustrating the front and side of a second embodiment of a chair employing our new design;

FIGURE 2 is an elevational view illustrating a side thereof;

FIGURE 3 is an elevational view illustrating the back thereof; and

FIGURE 4 is a plan view illustrating the top thereof.

The side of the chair not shown is the same in appearance as the side shown.

The dominant portions of the design reside in the features shown in full lines in the drawings.

We claim:

The ornamental design for a chair, substantially as shown and described.
